Primary Examiner — Stella Reid*Assistant Examiner* — Elizabeth J Oswecki(74) *Attorney, Agent, or Firm* — Harness, Dickey & Pierce, P.L.C.(57) **CLAIM**

The ornamental design for a money box, as shown and described.

DESCRIPTION

FIG. 1 is a perspective view of a money box embodying our new design;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a bottom view thereof;

FIG. 8 is a perspective view of a second embodiment of a money box showing our new design, this embodiment being identical to FIGS. 1-7 with the exception of the handle that swivels near the rear surface; and,

FIG. 9 is a perspective view illustrating two of the money boxes of FIG. 8 shown attached together in a used condition. In the drawings, the broken lines in FIGS. 1-4 and FIGS. 6-9 depict portions of the design that form no part of the claim.
